UNITED STATES PATENT OFFICE

WILLIAM H. FULCHER AND CHARLES H. WOOD, OF OAKLAND, CALIFORNIA

METHOD AND APPARATUS FOR MAKING CONTAINERS OF VEGETATIVE PULP

Application filed April 9, 1928. Serial No. 268,502.

This invention relates to a method and apparatus for the manufacture of rectangular containers of vegetative or other pulp.

It is the principal object of the present invention to provide an improved method and apparatus enabling rectangular containers to be inexpensively manufactured from vegetative or other pulp.

In carrying out the invention into practice a predetermined quantity of pulp suspended in water is placed in a contractile mold. A foraminous core corresponding to the interior dimensions of the container to be formed is then inserted into the mold and the latter is contracted to compress the pulp about the core and force the fluid into the core from whence it is drawn. The container thus formed is then partially dried, removed from the mold with the core, from the latter of which it is subsequently stripped and removed from the apparatus.

One form which the invention may assume is exemplified in the following description and illustrated by way of example in the accompanying drawings, in which:

Fig. 1 is a central vertical section through the machine with the stripper in place relative to the mold and the core being lowered into the mold.

Fig. 2 is a similar view taken at right angles to Fig. 1 and disclosing the container being stripped from the core and disposed on the pallet for removal from the apparatus.

Fig. 3 is a view in horizontal section through the mold structure of the machine.

Fig. 4 is a fragmentary view in plan showing the operating mechanism for the stripper and the core.

Fig. 5 is a fragmentary view in section through the pallet showing its control valve and the manner in which it is connected to the hollow shaft which supports it relative to the machine.

Fig. 6 is a perspective view of a container formed by our improved method and apparatus.

Fig. 7 is a transverse sectional view through the pallet control valve.

Fig. 8 is a fragmentary view in vertical central section through the mold structure

showing the parts in position forming a container.

Referring more particularly to the accompanying drawings 10 indicates a machine capable of use in the manufacture of rectangular containers from vegetative or other pulp. The machine here illustrated and described is designed for the manufacture of comparatively small rectangular cartons but can be made in various dimensions to produce containers varying in size from small cartons to burial caskets, without departing from the present invention. It is to be understood that the word container is here used to designate containers such as illustrated in Fig. 6 of the drawings of any and all dimensions and proportions.

As will be noted from Fig. 6, the container is formed of four side walls arranged at right angles to each other and a bottom wall, all of which are integrally formed.

In connection with the present machine we prefer to use vegetative pulp suspended in water but we do not limit ourselves to this use as various other pulp or fibrous substances may be utilized in lieu thereof.

The machine comprises a suitably constructed frame 11 rigidly supporting a mold structure 12. This mold structure is formed with a central rectangular well 13 of dimensions corresponding with the exterior dimensions of the container to be formed in the mold structure. At the two sides of the well 13 and at the ends thereof the mold structure is formed with horizontally and outwardly extending guideways 14. Side mold plates 15 and end mold plates 16 are reciprocably mounted in these guideways 14. The area and configuration of the inner faces of the side and end mold plates 15 and 16 are the same as the sides and ends of the well and the sides and ends of the container to be formed. The bottom of the well 13 is also formed with a vertical guideway 17 within which a bottom mold plate 18 is mounted for vertical reciprocation. This bottom mold plate 18 is of dimensions equalling the dimensions of the bottom of the well 13 and the bottom of the container to be formed in the mold structure.

When the mold plates 15, 16 and 18 are in their innermost positions, their contiguous edges come in contact and the mold plates 15, 16 and 18 constitute imperforate side, 5 end and bottom walls of the well 13.

To actuate the side and bottom mold plates 15 and 18, each of them is formed with outwardly converging cam faces 19. A pair of cams 20 are provided for each of these mold 10 plates, the cams being arranged at the opposite ends of the plates. The cams are formed with cam faces that are complementary to the cam faces 19 on the mold plates, so that movement of the cams of each pair 15 toward each other will cause the mold plate operated thereby to be moved to its innermost position. Anti-friction rollers are provided between the cam surfaces and between the bearing surfaces of the cams and guide- 20 ways to reduce the friction. When the side and bottom mold plates are to be moved to their outermost position, the cams 20 are withdrawn sufficiently to permit springs 21 provided for each of these plates to move the 25 mold plates to their outermost position.

To actuate the cams 20, we provide a horizontally disposed mold control shaft 22 which is journalled in the frame 11 centrally below the mold structure 12. Adjacent opposite 30 ends this shaft is provided with a pair of aligned eccentrics 23 which are keyed or otherwise suitably secured on the shaft. Each of these eccentrics is provided with an eccentric strap 24. Each eccentric strap is 35 pivotally connected to an upwardly extending shackle 25. These shackles are pivotally connected to a pair of vertically extending links 26 arranged at opposite sides of the mold structure. These links 26 are each connected to a pair of horizontally disposed toggle shafts 27 and 28 which are arranged horizontally in parallelism a spaced distance apart.

The toggle shafts 27 and 28 are connected 45 by means of toggle links 29 to the frame 11. The shafts 27 are also connected by means of toggle links 30 to the opposite end mold plates 16. At the ends of the shafts 27 toggle links 31 are provided which connect the shafts 50 27 with the actuating cams 20 of the side mold plates 15. The shafts 28 are also connected by means of toggle links 32 to the cams 20 which actuate the bottom mold plate 18.

It is obvious therefore that when the mold 55 plates are all in their outermost positions, one-half a revolution of the shaft 22 will actuate the toggle and link mechanism to move all of the mold plates 15, 16 and 18 to their innermost positions. For example, in 60 Fig. 2 the eccentric is shown at the top of its stroke with the cams 20 of the lower mold plate 18 withdrawn so that the mold plate 18 will be in its outermost position. Likewise, the end mold plates 16 are in their outermost 65 positions. Therefore, when the eccentrics 23

revolve one-half a revolution placing their high point at 180 degrees from that shown in Fig. 2, the shafts 27 and 28 will be drawn downwardly through the links 26, straightening out the toggle connections and causing 70 the two end mold plates to move to their innermost positions and simultaneously causing the cams 20 of the bottom mold plate to move inwardly and thereby elevate the bottom mold plate to its innermost position. 75 This movement also is transmitted through the links 31 to the cams 20 of the side mold plates 15, causing the latter to move inwardly to their innermost positions. As previously described when the mold plates are all arranged in their innermost positions, their edges adjoin to form the sides, ends and bottom of the central well 13.

It will be noticed that the springs which cause the side and bottom mold plates 15 and 18 to move outwardly are arranged on pipes 33 which are reciprocably mounted through the stationary part of the mold structure and connected to the mold plates. At their outer ends these pipes are fitted with 85 air regulators 34 which are in turn connected with flexible conduit 35. The springs are interposed between the elements 34 and the stationary part of the mold structure and are compressed when the mold plates move to 90 their innermost positions and are therefore capable of moving the mold plates 15 and 18 to their outermost positions when the cams 20 are withdrawn.

All of the mold plates are formed with 100 interior chambers with which the pipes 33 communicate. It is intended that these pipes 33 be all connected by means of the flexible conduit 35 to a source of fluid fuel such as gas which is burned in the chambers within 105 the plates to heat the same. Air openings are provided for these chambers to provide sufficient oxygen for burning gas therein. We may prefer, however, to provide electrical heating elements for the plates. The 110 reason for heating these plates will be hereinafter pointed out.

Extending vertically from the mold structure 12 and rigidly fixed relative thereto are four guide rods 36. The lower ends of these 115 rods are rigidly fixed to the mold structure which in turn is stationarily secured to the frame 11. At the top these rods are securely connected by the top portion of the frame 11. Disposed between these four rods 36 is a 120 core 37 which is in exact vertical alignment with the central well 13. The dimensions of this core 37 are less than the dimensions of the central well, so that when the core is disposed in the well the spacing between the 125 side walls and bottom of the well and between the bottom of the well and the bottom of the core will be equal to the thickness that it is desired to form the walls of the container. The side, end and bottom walls of 130

the core 37 are foraminous so that liquid may pass therethrough.

The construction of the core 37 is clearly illustrated in Figs. 1 and 8 of the drawings where it will be seen that the core is formed of a rigid rectangular metal casting having side walls and a bottom which are perforated. Externally of this casting are a plurality of layers of perforated plates and wire mesh or just wire mesh of mesh which decreases progressively in size. The outer layer of mesh is so fine that it will prevent any of the fibrous substances of the pulp from passing therethrough but will permit the water to be drawn rapidly through the walls of the core. The top of the core is enclosed by a fluid tight cover 38. Rigidly secured to the top of the core 37 and arranged thereabove are guide members 39 which are slidably disposed on the guide rods 36. This connection between the core and the guide rods 36 permits the core to be vertically reciprocated in accurate alignment with the well 13 of the mold structure. To vertically reciprocate the core 37, it is securely connected to the lower end of a vertically extending rack 40. This rack 40 extends upwardly from the core 37 and is guided in its vertical reciprocation by a flanged wheel 41 carried by the frame 11. The rack 40 is in mesh with a pinion 42 which is rigidly secured to a pair of pulleys 43 and 44. These pulleys 43 and 44 and the pinion are rotatably mounted on a countershaft 45 but are collared to prevent them from moving axially.

The pulley 44 is connected by means of a belt 46 to a pulley 47 mounted on a drive shaft 48. The pulley 43 is connected by means of a crossed belt 49 to a pulley 50 also mounted on the drive shaft 48. Clutches 51 and 52 are provided for the pulleys 47 and 50 which clutches may be alternately engaged by means of a control 53 so that either pulley may be clutched to the drive shaft 48.

It is obvious that when the pulley 47 is clutched to the shaft that it will drive the pinion 42 through the medium of the pulley 44 in one direction and when the pulley 50 is clutched to the shaft 48 the pinion 42 will be driven in the opposite direction due to the fact that the belt 49 is crossed. Thus, by manipulating the clutches 51 and 52, the pinion 42 may be revolved in opposite directions to reciprocate the rack 40 and the core 37.

Also reciprocably mounted on the rods 36 for vertical reciprocation in alignment with the well 13 and beneath the core 37 is a stripper 54 having a rectangular opening 55 formed centrally therein in vertical alignment with the core 37 and the mold well 13. The surfaces forming the perimeter of this opening 55 converge downwardly slightly. The dimensions of the opening at the bottom of the stripper are just slightly greater than the

dimensions of the core 37 so that the latter may reciprocate through the opening.

About the perimeter of the opening 55 at the bottom of the stripper is a downwardly projecting flange 56 which fits tightly within an opening formed in the top plate 57 of the mold structure. The thickness of the flange 56 is such, however, that it will abut against the top of the side and end mold plates. It is seen, however, that the outer perimeter of the flange 56 is tapered so that it will tightly fit within the opening in the top plate 57 to prevent leakage of liquid between them. The abutment between the outer perimeter of the flange 56 and the sides of the opening in the top plate 57 limits the downward movement of the stripper 54, so that the bottom edge of the flange 56 will be in alignment with the top edges of the side and end mold plates. To reciprocate the stripper 54, it is connected to two vertically extending racks 58 which mesh with pinions 59 secured on the countershaft 45. A pair of pulleys 60 and 61 are collared on this countershaft and are adapted to be driven in opposite directions by belts 62 and 63. The pulleys 60 and 61 are provided with clutches 64 which are adapted to be alternately operated by a control mechanism 65 to clutch either of the pulleys 60 and 61 to the shaft. When the pulley 60 is clutched to the shaft 45, it will be driven in one direction and when the pulley 61 is clutched to the shaft 45, the latter will be driven in the opposite direction. Therefore, by manipulating the clutches 64, the shaft 45 will be rotated in opposite directions to reciprocate the racks and the stripper 54.

The guide members of both the core 37 and the stripper 54 are provided with spring-pressed elements for engaging notches 66 and 67 in the vertical guide rods 36 to yieldably retain the stripper 54 and the core 37 in their proper relative positions at the upper end of their strokes.

When the stripper 54 is in its lowermost position or in operating position relative to the central well 13, we provide latch means for latching it in this position. This latch means is disclosed in Fig. 2 of the drawings and comprises a pair of keepers 68 arranged at opposite sides of the mold structure and capable of being simultaneously withdrawn by means of a handle 69. When the stripper 54 descends, it moves these keepers 68 outwardly against the action of springs 70 and when the stripper passes the keepers the latter engage the upper surface of the stripper and maintain it in its lowered position. The keepers as before stated may be actuated to release the stripper by means of the handle 69.

Latches 71 (see Fig. 8) are provided to latch the core 37 to the stripper when these elements are in their lowermost position rela-

tive to the mold structure. These latches may be manually released when it is desired to elevate the core relative to the stripper.

To deliver the pulp suspended in liquid to the well, we provide a delivery pipe 72 which is connected to a source of pulp supply. The lower end of this pipe 72 is fitted with a swivel nozzle 73 controlled by a valve 74. A valve 75 is interposed in the pipe 72 at a predetermined space above the nozzle 73. It is intended that the cubic capacity of the pipe 72 between the valve 75 and the nozzle 73 be equal to the amount of liquid and pulp necessary for the manufacture of a container. When desiring to fill the well with pulp, the nozzle 73 is swung to the position indicated in Fig. 2 and the valve 74 is opened permitting the pulp to discharge into the central well 13. When the flow stops, the valve 74 is closed and the nozzle 73 is swung away from its position over the well to an unobstructing position. The valve 75 is then opened and the pipe 72 again filled with the pulp after which the valve 75 is closed.

In operation of the device, when the well 13 has been supplied with pulp the mold plates 15, 16 and 18 are in the positions shown in Figs. 1 and 2 and the stripper 54 and core 37 are in the positions illustrated in Fig. 2 where they are yieldably supported by the notches 66 and 67 in the guide rods 36.

The shaft 45 is then revolved to rotate the pinions 59 a sufficient amount to lower the racks 58 to place the stripper 54 in its lowermost position. The pinion 42 is then revolved to lower the core 37 to position within the well 13. It will be noticed from Figs. 1 and 8 that at its upper end the core 37 is formed with a tapered surface 37a which coincides with the taper of the perimeter of the opening through the stripper 54. When this tapered surface 37a contacts with the tapered perimeter of the opening through the stripper 54, the core 37 will be in proper position within the well.

When the stripper and core have been lowered to position the latches 68 and 71 will latch them in position. It is seen that due to the water tight joint between the stripper 54 and the cover plate 57 of the mold structure and the tight joint between the tapered surfaces 37a of the core and the perimeter of the opening through the stripper 54, the fluid and pulp in the well will be confined therein.

As before stated the core 37 is foraminous so as to permit the passage of the water through its walls but preventing the passage of the pulp substances. Therefore, all of the pulp will be confined to the exterior of the core while the fluid may pass into the core.

After the parts are in the positions just described, the shaft 22 is revolved one-half a revolution to move all of the mold plates 15, 16 and 18 to their innermost positions.

The movement of these plates will force the fluid through the walls of the core and compress the pulp within the spaces surrounding the core between the outer surface thereof and the surfaces of the mold plates.

It may be desired to engrave the surfaces of the mold plates so as to form indicia on the box. These mold plates as before described are heated and when the water is withdrawn from the core, the heat tends to partially dry the formed container.

As the mold plates are operated a suction is created in a pipe 76, the lower open end of which extends through the tight cover 38 of the core to a point contiguous to the bottom of the core. This suction withdraws all of the water and moisture from within the core. Thus, this suction and the heated mold plates 15, 16 and 18 cause partial drying of the formed container.

The next step is to revolve the pinions 59 and 42 in unison to elevate the stripper 54 and the core 37 in unison to a point where the stripper 54 has reached its uppermost position. The suction through the pipe 76 is discontinued and air under pressure is discharged therethrough into the core. The pressure of this air slightly expands the container on the core to loosen it from the core. Continued upward movement of the core 37 removes the core from the container. It is seen that the flange 56 of the stripper 54 engages the upper edges of the container and strips it from the core 37 as the latter is withdrawn therefrom (see Fig. 2).

Just prior to stripping the container from the core 37 a flat hollow pallet 77 is arranged beneath the container to receive the same when it is stripped from the core. This pallet is disposed horizontally and is connected to a vertical hollow shaft 78 rotatably supported at its ends by the frame 11 at one side of the machine. This hollow shaft 78 is connected with a suction line 79 adapted to create a suction within the pallet and through the perforated top 80 thereof to cause the container to adhere to the pallet. The pallet 77 is rotatably connected to the shaft 78 so that after it has been swung with the container to a position at the exterior of the machine, it may be revolved to invert the container and deliver it to a receiving means in inverted position. When the container is inverted the suction within the pallet 77 causes the container to adhere to the pallet. When this suction is discontinued the container will be released from the pallet.

We prefer to deliver the container in an inverted position because we have found in actual practice that this maintains the edges of the container perfectly flat and prevents the container from warping.

To discontinue the suction through the pallet 77 and to revolve the same we provide

a valve shaft 81 having a valve 82 thereon which cooperates with a valve seat 83. When the valve shaft 81 is revolved the entire pallet revolves due to an extension 84 on the valve.

5 To operate the valve to discontinue the suction it is moved axially against the seat 83.

From the foregoing it is obvious that we have provided an apparatus enabling containers to be comparatively inexpensively

10 manufactured from vegetative or other pulp and while we have shown the preferred form of our invention, it is to be understood that various changes may be made in its construction by those skilled in the art without departing from the spirit of the invention as

15 defined in the appended claims.

Having thus described our invention, what we claim and desire to secure by Letters Patent is:

20 1. An apparatus of the character described comprising a contractile mold having imperforate side, end and bottom walls and open at the top and into which pulp suspended in liquid may be placed, a rectangular 25 foraminous core adapted to be suspended within the mold and movable into and out of the same through the open top thereof, means for contracting the mold about the core to compress the pulp in the spaces intermediate the mold and core to form a container, and means for withdrawing the liquid from the mold and core as the container is formed.

2. An apparatus of the character described comprising a mold having imperforate sides, ends and bottom and open at the top, a rectangular core adapted to be suspended within the mold and movable into and out of the same through the open top thereof, means for simultaneously moving the sides, ends and bottom of the mold toward the core to a point a predetermined distance from the core to compress the pulp in the spaces between the sides, ends and bottom of the 45 mold and core to form a container, said core permitting the passage of fluid therethrough, and means for withdrawing the liquid from the core.

3. An apparatus of the character described comprising a contractile mold having imperforate side, end and bottom walls and into which pulp suspended in liquid may be placed, a rigid foraminous core adapted to be positioned within the mold and movable into and out of the same through the open top thereof, said mold being adapted to be contracted about the core to force the liquid into the core and compress the pulp in the spaces intermediate the mold and the 55 core to form a container, and means for stripping the container thus formed from the core after the core has been removed from the mold.

4. An apparatus of the character described comprising a rectangular contractile

mold having imperforate side, end and bottom walls and into which pulp suspended in liquid may be placed, means for discharging a predetermined amount of pulp and liquid into the mold, a rigid rectangular foraminous core and movable into and out of the mold through the open top thereof and adapted to be positioned within the mold, said mold being adapted to be contracted about the core to force the liquid into the core and compress the pulp in the spaces intermediate the mold and the core to form a container about the core, and means for withdrawing the liquid from the core.

5. An apparatus of the character described comprising a contractile mold having imperforate side, end and bottom walls and open at the top, means for heating said mold, means for discharging a predetermined quantity of pulp suspended in liquid in the mold, a rigid rectangular foraminous core movable into and out of the mold through the open top thereof and adapted to be positioned within the mold, said mold being adapted to be contracted about the core to force the liquid into the core and compress the pulp in the spaces intermediate the mold and core to form a container, means for simultaneously withdrawing the water from the core, and means for stripping the container from the core after the container has been formed.

6. An apparatus of the character described comprising a mold having imperforate sides, ends and bottom and open at the top, a rigid rectangular foraminous core movable into and out of the mold through the open top thereof and adapted to be suspended within the mold, means for discharging a predetermined quantity of pulp and liquid into the mold prior to the positioning of the core therein, means for moving the sides, ends and bottom of the mold toward the core to a point a predetermined distance from the core to compress the pulp about the core and to force the liquid into the core, means for simultaneously withdrawing the liquid from the core, and means for loosening the container from the core and thereafter stripping the container from the core.

7. An apparatus of the character described comprising a mold having imperforate sides, ends and bottom and open at the top, means for discharging a predetermined quantity of liquid and pulp into the mold, an operative foraminous core movable into and out of the mold through the open top thereof and adapted to be suspended within the mold, means forming a fluid tight joint between the top of the core and the top of the mold, means for simultaneously moving the sides, ends and bottom of the mold toward the core and to a point a predetermined distance from the core to compress the pulp about the core and to force the liquid into the core, and means

for withdrawing said liquid as the container is formed.

8. An apparatus of the character described comprising a mold having imperforate sides, ends and bottom and open at the top, means for discharging a predetermined quantity of liquid and pulp into the mold, an operative foraminous core movable into and out of the mold through the open top thereof and adapted to be suspended within the mold, means forming a fluid tight joint between the top of the core and the top of the mold, means for simultaneously moving the sides, ends and bottom of the mold toward the core and to a point a predetermined distance from the core to compress the pulp about the core and to force the liquid into the core, means for withdrawing said liquid as the container is formed, means for heating the sides, ends and bottom of the mold, means for loosening the container from the core after the latter has been removed from the mold, and means for stripping the container from the core after it has been loosened therefrom.
9. An apparatus of the character described comprising a mold having imperforate sides, ends and bottom and open at the top, means for discharging a predetermined quantity of liquid and pulp into the mold, an operative foraminous core movable into and out of the mold through the open top thereof and adapted to be suspended within the mold, means forming a fluid tight joint between the top of the core and the top of the mold, means for simultaneously moving the sides, ends and bottom of the mold toward the core and to a point a predetermined distance from the core to compress the pulp about the core and to force the liquid into the core, means for withdrawing said liquid as the container is formed, means for heating the sides, ends and bottom of the mold, means for loosening the container from the core after the latter has been removed from the mold, means for stripping the container from the core after it has been loosened therefrom, means for receiving the container as it is stripped from the core, said means being operative to remove the container from the apparatus and deliver it in inverted position.
